UNITED STATES PATENT OFFICE.

SIDNEY WILLIAMS, OF CRANSTON, RHODE ISLAND.

DESIGN FOR A COMB.

No. 39,053.

Specification for Design.

Patented Feb. 4, 1908.

Application filed December 14, 1907. Serial No. 406,565. Term of patent 3½ years.

To all whom it may concern:

Be it known that I, SIDNEY WILLIAMS, a citizen of the United States, residing at Cranston, in the county of Providence and State of Rhode Island, have invented a certain new, original, and ornamental Design for a Comb, of which the following is a specification.

The figure is a plan view of a comb showing my new design.

I claim,
The ornamental design for a comb as shown.

SIDNEY WILLIAMS.
